UNITED STATES PATENT OFFICE.

GEORGE SPANGLER, OF LEIPSIC, OHIO.

MONKEY WRENCH.

Application filed January 22, 1925. Serial No. 4,037.

This invention aims to provide a wrench having a quick-acting jaw, the construction being such that, after the jaw has been brought up against the work, the jaw can 5 tilt and grip the shank of the wrench, thereby taking much or all of the strain off the latch mechanism which holds the movable jaw in any position to which it may have been adjusted.

10 It is within the province of the disclosure to improve generally and to enhance the utility of devices of that sort to which the invention appertains.

With the above and other objects in view 15 which will appear as the description proceeds, the invention resides in the combination and arrangement of parts and in the details of construction hereinafter described and claimed, it being understood that 20 changes in the precise embodiment of the invention herein disclosed may be made within the scope of what is claimed without departing from the spirit of the invention.

25 In the accompanying drawings:—

Figure 1 shows in side elevation a wrench constructed in accordance with the invention; Fig. 2 is an elevation wherein the wrench is viewed at right angles to the showing of Fig. 1; Fig. 3 is a fragmental 30 longitudinal section wherein parts are broken away; and Fig. 4 is a cross section on the line 4—4 of Fig. 3.

The wrench forming the subject-matter 35 of this application comprises a handle 1 including a grip 2 having a longitudinal passage 3 receiving the reduced end 4 of a shank 5 having a shoulder 6 which engages the inner end of the grip 2, the shank 5 carrying a fixed jaw 7, securing elements 8 40 uniting the grip 2 with the end 4 of the shank 5, the cross sectional area of the end 4 of the shank 5 being such that it fills the passage 3 but partially.

A rider 9 is mounted for right-line reciprocation on the shank 5 and is supplied with 45 a rack 10 in slidable contact with the members 4 and 5, the rack being adapted to extend backwardly into the unencumbered portion of the passage 3. A latch 11 is 50 located between the ears 12 on the grip 2 and is mounted on a pivot element 14 carried by the ears, the latch being adapted to

cooperate at one end with the rack 10, the compression spring 25 being interposed between the grip 2 and the other end of the 55 latch 11 to hold the latch normally engaged with the rack 10.

The rider 9 has a recess 15 into which extends a tongue 16 on a movable jaw 17 having an opening 18 for the passage of the 60 shank 5, the tongue 16 being supplied with an opening 19 receiving a pivot element 20 carried by the rider 9 and extended across the recess 15.

In practical operation, when the latch 11 65 is disengaged from the rack 10, the jaw 17 should be shifted quickly into any desired position, so as to cooperate with the fixed jaw 17 in engaging an object, as indicated in Fig. 3.

Note that the opening 19 in the tongue 16 of the movable jaw 17 is considerably larger than the cross section of the pivot element 20, and observe that the opening 18 of the movable jaw 17 is of greater cross section 70 than the cross sectional area of the shank 5, 75 as indicated in Fig. 3. The result is that after the jaw 17 has been brought up against the work, the jaw can tilt a little, gripping the shank 5 at diagonally opposite points indicated by the numeral 21, a large amount of strain thus being taken off the latch 11.

Having thus described the invention, what is claimed is:—

A wrench comprising a shank having a 85 fixed jaw, a rider mounted to slide on the shank, latch mechanism cooperating with the shank and the rider to hold the rider in adjusted positions longitudinally of the shank, and a movable jaw cooperating with 90 the fixed jaw and having an opening receiving the shank, the movable jaw being loosely pivoted to the rider, and the opening in the movable jaw being large enough so that the movable jaw can tilt with respect to the 95 rider when engaged with the work, thereby causing the movable jaw to grip the shank at diagonally opposite points and relieve the strain on the latch mechanism.

In testimony that I claim the foregoing 100 as my own, I have hereto affixed my signature.

GEORGE SPANGLER.
